TOOLHEAD LOCK

William L. Dysart and Alonzo L. Adkins,
Lebanon, Ohio

Application December 15, 1943, Serial No. 514,414

6 Claims. (Cl. 306—33)

This invention relates to an improved tool head lock particularly adapted for use in conjunction with carpenter's tools such as hammers, hatchets and the like, although not limited to such use.

As is well known, a simple metal wedge has heretofore been widely used as a means of locking, say a hammer head or the like on the handle therefor, the wedge being driven into the forward end of the handle to expand the wood in the eye of the tool head. However, such expedient has proven ineffective and unsatisfactory for the reason that, in a great many instances, the wedge sooner or later becomes loose with the result that the tool head also becomes loose on the handle.

An object of the present invention, therefore, is to provide a lock embodying a wedge which, under ordinary use of a tool, will not become loose and will permanently and solidly secure the tool head on the handle therefor.

A further object of the invention is to provide a wedge which, after being driven into the forward end of the tool handle to expand the wood thereof in the eye of the tool head, may be distorted to engage the handle externally of the normal lines of the wedge for locking the wedge solidly in position.

Another object of the invention is to provide a wedge having tongues at opposite edges thereof which, after the wedge has been driven into the forward end of the handle, may be bent laterally to project beyond the lines of the wedge and bite into the wood of the handle for locking the wedge against retrograde movement.

Still another object of the invention is to provide a wedge wherein a short shoulder will be provided at the base of each tongue to furnish a fulcrum, so that by hammering against the tongue toward the tip thereof, the tongue will be caused to bend laterally outward near the shoulder and sink into the wood of the handle.

A further object of the invention is to provide a wedge wherein the metal of the wedge will be more or less malleable, as contrasted with a highly resilient metal, so that when the tongues are bent laterally to engage the wood of the handle, said tongues will remain in their bent or distorted shape instead of actively tending to spring back to release the wedge should the forward end of the handle shrink.

And the invention seeks, as a still further object, to provide a wedge wherein access to the tongues may be readily had at the proper angle for hammering the tongues laterally after the wedge is driven into place.

Other and incidental objects of the invention

will appear during the course of the following description, and in the drawing:

Figure 1 is a view partly in side elevation and partly in section showing our improved lock in conjunction with a conventional hammer, this view illustrating the manner in which a punch is used to bend the tongues of the wedge laterally.

Figure 2 is a view similar to Figure 1 and showing the tongues bent laterally.

10. Figure 3 is a detail side elevation of the wedge.

Figure 4 is a vertical, transverse section showing the diagonal channels which are provided to receive the punch employed for bending the wedge tongues.

15. Figure 5 is a detail side elevation showing the tongues bent laterally.

Figure 6 is an edge elevation of the wedge.

Figure 7 is a top plan view of the wedge.

20. Figure 8 is a perspective view of the punch employed.

Referring now more particularly to the drawing, it will be seen that we have, for convenience, shown our improved locking device in conjunction with a conventional hammer embodying the usual metal head 10 having an eye 11 to tightly receive the forward end of the wooden handle 12. As will be understood as the description proceeds, the invention is well adapted for use in conjunction with many other tools and we do not, therefore, wish to be limited in this respect.

In carrying the invention into effect, we employ a metal wedge 13 which, after the handle is fitted in the eye 11, is driven into the forward end of the handle for expanding the wood thereof within said eye. As seen in Figures 3 and 6 of the drawing, the wedge is tapered at its sides and edges and these surfaces are smooth so that the wedge may be readily driven into place. In the present instance, the upper edge of the wedge is shown as curved to conform to the curvature of the upper face of the head 10. However, this detail is immaterial and the upper edge of the wedge may be square if so desired.

40. 45. Suitably cut or otherwise formed in the wedge from the side edges thereof are like diagonal slots 14 which slope downwardly and inwardly toward the tip of the wedge at the same angle. The upper ends of these slots are preferably located ap-

proximately midway between the ends of the wedge. Similarly formed in the wedge from the side edges thereof a short distance below the slots 14 are parallel, diagonal slots 15 which are much shorter than the slots 14, say about half as long more or less. The slots 14 may thus be identified

as the long slots and the slots 15 as the short slots.

As will now be seen, a diagonal tongue 16 is defined between each pair of slots 14 and 15 and, as will now be appreciated, these tongues 16 normally lie flush with the side faces of the wedge as well as the side edges thereof conforming to the lines of the wedge. Further, it is to be noted that in the angles between the slots 15 and the side edges of the wedge short triangular shoulders 17 are defined. These shoulders, like the tongues 16, normally conform to the lines of the wedge.

Formed in the wedge from the upper end thereof are intersecting, diagonal channels 18 each sloping from a point near one side edge of the wedge to open at substantially a right angle thereto into the diagonally opposite slot 16 located at the other side edge of the wedge. These channels enter the slots about midway of the depth thereof.

In conjunction with the wedge 13 we provide a punch 19, seen in detail in Figure 8 of the drawing. The punch may be provided with a knurled stock, and projecting therefrom is a reduced stem 20 of a diameter to removably fit more or less snugly in either of the channels 18 of the wedge selectively.

It is now to be noted that the wedge 13 is preferably formed of a suitable metal which is more or less malleable, as distinguished from a metal having a pronounced characteristic of resiliency. Thus, when the tongues 16 are bent, they will remain permanently in their bent or distorted shape instead of pronouncedly tending, as would spring tongues, to flex or spring back to original or normal shape or disposition.

In practical use, the wedge 13 is first driven into the forward end of the handle, as seen in Figure 1 of the drawing, so that the wedge lies flush with the upper face of the head 10. The stem 20 of the punch 19 is then inserted in one of the channels 18 to rest against the corresponding tongue 16, after which the punch is struck with a hammer or the like to pound against the tongue and bend the tongue laterally into the wood of the handle. Having bent one tongue, the punch is reversed to extend within the other of the channels 18, when the hammering operation is repeated to bend the other tongue laterally into the wood of the handle. As the stem of the punch selectively fits either channel snugly, the forward end of the stem will be prevented from riding along the tongues under impact of the hammer blows on the punch.

Assuming the channels 18 to be projected, attention is now directed to the fact that the slots 15 are of a depth to extend past the lower ends of the channels so that either one or the other of these slots will lie beneath the forward end of the stem 20 of the punch 19 during the hammering operation on the tongues 16. Thus, the slots 15 will provide clearance tending to cause the tongues to curl laterally outward from the base ends thereof under impact of the punch until the tongues strike the upper ends of the shoulders 17. The shoulders 17 will then provide fulcrums for the tongues therebeneath so that as the hammering operation is continued,

the tongues will be caused to further bend laterally outward and bite into the wood of the handle at the tips of the tongues, as shown in Figure 2 of the drawing, for locking the wedge solidly in position.

Having thus described our invention, what we claim is:

1. A tool head lock including a wedge adapted to be driven into the forward end of a tool handle and provided at its inner end portion with a tongue hidden by the material of the handle when the wedge is in place but accessible through the wedge to be bent into the material of the handle without disturbing the wedge for locking the wedge in position.
2. A tool head lock including a wedge adapted to be driven into the forward end of a handle, and a tongue carried by the wedge, the wedge being formed with a channel adapted to receive a punch to contact and bend the tongue laterally into the material of the handle for locking the wedge in position.
3. A tool head lock including a wedge adapted to be driven into the forward end of a tool handle and formed at one side edge thereof with a diagonal slot providing a tongue, the wedge being formed with a channel opening into said slot and adapted to receive a punch to contact the tongue after the wedge is in place for bending the tongue laterally into the material of the handle for locking the wedge in position.
4. A tool head lock including a wedge adapted to be driven into the forward end of a tool handle and provided at one side edge thereof with spaced long and short diagonal slots defining an intervening tongue as well as a shoulder between the short slot and said edge of the wedge beneath the tongue, the wedge being formed with a diagonal channel opening into the long slot and adapted to receive a punch to contact the tongue after the wedge is in place and bend the tongue laterally across said shoulder into the material of the handle for locking the wedge in position.
5. A tool head lock including a wedge adapted to be driven into the forward end of a tool handle and provided with a channel therethrough leading from the outer end of the wedge and with a tongue opposite the inner end of said channel whereby a tool may be inserted in said channel to engage and bend the tongue into the material of the handle after the wedge is driven into position.
6. A tool head lock including a wedge of normal symmetrical contour and provided with a tongue normally lying within the lines of the wedge to conform to the symmetrical contour thereof and permit the wedge to be driven into the forward end of a tool handle without mutilation of the material thereof by said tongue, the wedge being provided with a channel leading from the outer end of the wedge and terminating opposite said tongue whereby a tool may be inserted in said channel to engage and bend the tongue into the material of the handle after the wedge is driven into position.
